TIRE FABRIC

Fletcher Chadwick, Preston, England, assignor to
 Preston Tyre Fabric Manufacturing Company
 Limited, Higher Walton, Preston, England, a
 limited-liability company of Great Britain

Application July 10, 1936, Serial No. 89,877
 In Great Britain April 16, 1936

4 Claims. (Cl. 139—420)

In the manufacture of tire fabrics and analogous fabrics consisting of woven textile threads it is customary to employ warp threads of plied or cabled yarns, commonly referred to as cords, and weft of single threads. This is the simplest and most economical method of forming such fabrics, inasmuch as the weft threads serve to hold the warps together and, as one advantageous result of this, the warp threads being held and controlled may separate sufficiently under the heavy pressure of the calender rolls in the rubberizing or coating of the fabric with rubber, so that these warp threads are more thoroughly coated as to their surfaces than can be possible where parallel warps only without weft are passed through the calender, as in that case the warps must necessarily be held closely together during the treatment to prevent displacement.

With the known forms of woven fabric however serious disadvantages subsist. The action of the calender rolls causes relative movement of the crossing warp and weft threads, with consequent distortion and a sawing action between them at their crossing points. Again, the heavy pressure exerted by the calender rolls itself prevents any application of the coating rubber to the contacting threads at these points and, most serious of all, when the tire fabric is in use as a tire cloth the continual flexing of the same causes a proportionately continual sawing action between the crossing threads at these points, deleterious heat being set up by the friction with cutting of the warp threads and a considerable shortening of the life of the fabric.

The present invention is directed to the provision of a tire fabric in which these disadvantages will not appear, and according to such invention a tire fabric is formed with warp threads of usual character, and weft threads of rubber or rubber compound in a plastic and extensible condition. The expression "extensible" as herein employed in connection with a thread is intended to denote a higher quality of elasticity than that possessed by the ordinary cotton thread.

The effect of thus forming the fabric is that the life and efficiency of the same are raised to the maximum, the faults inherent in an ordinary cotton weft thread when used in such fabric being avoided.

The annexed diagrams are given to assist in the explanation of the invention, Figure 1 showing in section the warp threads with a weft thread after weaving; and Figure 2 being a diagram of the warp and weft threads after the

calender rolls have been applied thereto, in the usual coating or rubberizing.

Taking the warp threads 3 and weft threads 4 as seen in Figure 1, and assuming that the weft threads 4 are of cotton as usual, it will be evident that when the calender rolls are applied the unyielding nature of the said weft threads would be conducive to the disadvantages hereinbefore enumerated, the closing together of the warp threads due to calendering pressure leaving the weft threads as potential sawing media across the warp threads 3. If however the weft threads such as 4 are of rubber, the effect of the calendering is as shown diagrammatically in Figure 2. That is to say, the rubber weft threads, when the calendering pressure is applied, yield and assume a position relative to the warp threads as shown diagrammatically, the crossing warp and weft threads thus, on the fabric flexing transversely of the warp threads, moving together.

It is found that, employing rubber thread as weft thread, the finer the thread, within limits as will be understood, the better the ultimate effect. A convenient size of rubber thread is one which as to dimensions is about equivalent to 50's yarn counts, but I may employ any size which suits the purpose.

An advantage of the use of rubber or rubber compound weft threads is that, whereas in known manufacture of tire fabrics with warp threads and the usual weft threads, the pressure of the calender roll itself prevents access of the rubber in the rubberizing or coating to the space between a warp thread and weft thread at their point of junction as hereinbefore stated, the use of weft threads of rubber or rubber compounds ensures "rubberizing" at that point and further the said weft threads become homogeneous with the rubber covering. The plasticity of the rubber or rubber compound permits of the fabric lying more flat or more evenly surfaced than with a non-plastic material such as ordinary cotton yarn as usually employed. Less rubber therefore is required in the coating or rubberizing, owing to the reduction in the area of the undulatory surface of the fabric.

I claim:

1. A tire fabric consisting of warp threads of tire cord, and weft threads, all the temporarily binding weft threads being of rubber in a plastic and extensible condition.
2. A tire fabric consisting of warp threads of tire cord, and weft threads, all the temporarily binding weft threads being of rubber compound in a plastic and extensible condition.

3. A rubber-covered tire fabric consisting of warp threads of tire cord and weft threads which have previously served as temporary binding threads for the warps, the weft threads being of plastic and extensible rubber and being incorporated with and homogeneous with the rubber covering.
4. A rubber-covered tire fabric consisting of

warp threads of tire cord and weft threads, the weft threads which have previously served as temporary binding threads for the warps being of plastic and extensible rubber compound, and being incorporated with and homogeneous with the rubber covering.

FLETCHER CHADWICK.
